UNITED STATES PATENT OFFICE.

ELMER E. KOEHLER, OF ROCHESTER, NEW YORK.

METHOD OF AND MEANS FOR BRACING THE CONTENTS OF CARS OR THE LIKE.

1,088,347.

Specification of Letters Patent. Patented Feb. 24, 1914.

Application filed November 4, 1913. Serial No. 799,180.

To all whom it may concern:

Be it known that I, ELMER E. KOEHLER, a citizen of the United States, residing at Rochester, in the county of Monroe and 5 State of New York, have invented a new and useful Improvement in Methods of and Means for Bracing the Contents of Cars or the like, of which the following is a specification.

10 My invention relates to an improved method and means for bracing the contents of cars, or the like, and is especially designed for the bracing of eggs in transit in cars, though it is not my intention to be understood as intending to limit it to this 15 particular use.

In the loading more especially of railway cars with eggs or other fragile articles, the 20 number of cases thereof placed in the car almost invariably is insufficient to cause the top row of cases to be coextensive with the area covered by the rows of cases beneath, and the non-uniformity of the dimensions of the cases and the dimensions of the cars, also 25 prevent the cases from snugly fitting the car. As a consequence the cases are sufficiently free to shift in the car especially when the latter is subjected to severe jolts as often occurs in starting, stopping and side-track- 30 ing cars and this has resulted in a large percentage of loss by the breaking of the contents of the cases, this loss in the case of eggs alone being so great as to prompt commercial and railroad associations to appoint 35 a committee, one of the members of which is a Government official, to investigate the matter and report on ways and means to reduce loss from this cause.

My object is to provide for the bracing of 40 the cases in the cars, or the like, and thus minimize, if not entirely eliminate, losses which have resulted as hereinbefore stated.

Referring to the accompanying drawings— Figure 1 is a plan sectional view of a rail- 45 way car showing its interior packed with cases, as for example, egg cases, and braced therein by my improved bracing means. Fig. 2 is a vertical sectional elevation of the same, the section being taken at the line 50 2 on Fig. 1 and viewed in the direction of the arrow. Fig. 3 shows by a plan sec- tional view on line 3 of Fig. 4, another ar- rangement of my improved bracing means

suitable where the cases in the car are positioned in one end only thereof. Fig. 4 is a 55 section taken at the line 4 on Fig. 3 and viewed in the direction of the arrow. Fig. 5 is a view similar to Fig. 1, the section being taken at the line 5 on Fig. 6 and viewed in the direction of the arrow, of still another arrangement of my improved bracing means for bracing cases placed in the car in a different position. Fig. 7 is a perspective view of one of the similar racks forming my improved bracing means; and Figs. 8, 9, 10 60 and 11, sections taken through pluralities of the racks of Fig. 7, interfitting with each other in certain of the different positions of use.

In the packing of cases into a car, variations in the inside of the car, or in the cases, or both, cause spaces to be left between cases, and the shipments are almost invariably of such a number of cases that the uppermost row thereof will not be complete, or, in other 70 words, will not contain as many cases as the rows beneath. Furthermore, it is desirable to place relatively small shipments of cases at one end of a car with the result that the arrangements of cases in the car under the 75 different conditions met with, are almost of infinite number.

While my improved means have been devised with a view to providing for the bracing of cases in their different arrangements 85 in the car, I have not attempted to illustrate my improved means for all of the arrangements to which they are applicable, but only to such arrangements as are most commonly met with in practice and which serve to most 90 forcibly illustrate the character and use of my improved means.

My invention consists in its preferred em- bodiment of a plurality of similar racks, 95 preferably of wood, one of which is illus- trated in Fig. 7, and, as shown, comprising a plurality of longitudinally extending par- allel slats 11 connected together at intervals by parallel cross-pieces 12, which extend at right angles to the slats, these cross-pieces 100 being secured in any suitable manner to the same sides of the slats 11 as represented and preferably a distance from the ends of the slats equal to substantially one-half the width of the pieces 12. The slats 11, prefer- 105 ably four in number, are preferably spaced

apart a distance slightly in excess of their width, in practice these slats being about four inches wide and the spaces between them about four and one-eighth inches wide, 5 and the cross-pieces 12 preferably about four inches wide with the spaces between them of slightly greater width than the distance between the inside edges of the two slats at the opposite edges of the rack.

10 From the foregoing description it will be readily understood that the racks may be interfitted with each other at their slats, to cause the racks to extend in parallel relation, or interfitted with each other to cause 15 the racks to extend at right angles to each other by fitting one of the racks at a cross-piece 12 thereon into one of the spaces between the slats 11 of the other rack.

In the arrangement illustrated in Figs. 1 20 and 2, egg cases represented at 13 are arranged in groups at opposite ends of the car indicated at 14, thus leaving a space 15 between the groups of cases near the middle of the car, and the uppermost row of each 25 group of cases consists of a less number of cases than the rows beneath it. In filling out the space 15 between the two groups of cases five of the racks shown in Fig. 7 are employed, these racks being arranged in parallel relation. The two lower center racks 30 are placed flatwise together at their cross-pieces 12, the third rack is superposed on these two center racks, and the two outer racks are interfitted at their slats 11 with 35 slats of the two center racks, by fitting the lower slats of the outer racks into the spaces between the upper slats of each of the center racks, as more clearly represented in Fig. 8, thus causing the rack structure to extend 40 above the cases 13. The incomplete top row at the left hand end of the car is braced by certain of the racks shown in Fig. 7. In this arrangement three racks are employed, two lying flat at their cross-pieces on the cases 45 adjacent to the incomplete upper row thereof, one of the two racks lying against the end of the incomplete row of cases and the other of the two racks against the upright racks which fill out the space 15 in the center of the car, and the third rack extending 50 parallel with these two horizontally disposed racks and interfitting at its slats with the slats 11 of these two horizontal racks, as more clearly illustrated in Fig. 9. At 55 the other end of the car one rack is laid on the top of the uppermost complete row of cases and against the side of the incomplete top row of cases to extend transversely of the car and another is laid lengthwise of 60 the car to fit between the horizontally disposed rack and the end of the car, as clearly illustrated in Figs. 1, 2 and 10. It will be manifest that if the space to be filled with 65 racks for preventing the cases from shifting in the car is less at either end of the car than

as shown, the three racks at the left-hand end of the car may be more compactly interfitting and the racks at the other end may be interfitting to cause a cross-piece 12 of one rack to interfit between any of the adjacent 70 slats 11 of the other rack, depending on the size of the space to be filled.

In Figs. 3 and 4, I have shown my improved means applied to a car where the cases are stacked in one end only thereof. 75 In this case six racks are employed. One is nailed to the floor at the ends of the rows of cases with its slats uppermost, four are arranged in two upright groups, the slats of each group fitting against each other at 80 their cross-pieces 12, one group being laid against the end of the cases and edgewise upon the horizontal rack and the other group against the first referred to group to extend at its lower end into the space between the two adjacent slats 11 of the horizontal rack, and the sixth rack is interfitted in an inclined position with a slat of the horizontal rack and with a slat on the outermost rack of the two groups thereof. The 85 arrangement of the racks just described thus serve to very effectually brace the cases against shifting in the car.

In Figs. 5 and 6, the arrangement of the cases is such as to produce a space at the 95 center of the car between the two groups of cases and an incomplete row in only one of the groups. The central space in this arrangement of the cases, shown to be of less width than that in Figs. 1 and 2 to 100 illustrate another condition met in practice, is filled out by two racks placed together at their cross-pieces 12. The upper incomplete row of cases is braced by two of the racks extending transversely of the car and 105 interfitting at their slats 11 to fill out the space between the upper row of the group of cases at one end of the car and the incomplete upper row of the group at the other end of the car.

The examples of arrangements of cases and their relation to the interior of the car are sufficient to clearly disclose the manner in which the racks may be used; and from this disclosure it will be manifest that the 115 racks may be caused to fill out the various sized spaces presented in practice, as the racks are adapted to be grouped together and interfitted with each other in parallel or transverse relation to form a large number of combinations.

The racks also present the advantage of cushioning the cases in case of jolts by reason of their resiliency, when the racks are of the preferred construction, namely, when 125 made of relatively thin strips of wood.

What I claim as new and desire to secure by Letters Patent is—

1. Means for the purpose set forth comprising a plurality of racks formed of lon- 130

itudinally extending parallel slats and cross-pieces connecting them together, adapted to be interfitted with each other in parallel relation.

5. 2. Means for the purpose set forth comprising a plurality of racks formed of longitudinally extending parallel slats and

cross-pieces connecting them together, adapted to be interfitted with each other in parallel transverse relation.

ELMER E. KOEHLER.

In presence of—

A. C. FISCHER,

O. C. AVISUS.
